UNITED STATES PATENT OFFICE.

BENJAMIN NOYES, OF BOSTON, MASSACHUSETTS.

RUCHING FOR DECORATIVE PURPOSES.

SPECIFICATION forming part of Letters Patent No. 336,149, dated February 16, 1886,

Application filed February 21, 1881. Serial No. 26,697. (Model.)

To all whom it may concern:

Be it known that I, BENJAMIN NOYES, of Boston, in the county of Suffolk and State of Massachusetts, have invented certain Improvements in Ruching for Decorating, of which the following is a specification.

This invention has for its object to provide an improved ruching for decorating rooms, pillars, and arches, composed of paper, and adapted for use chiefly as a substitute for the well-known decorating material made by securing natural evergreen material to a cord or rope.

My invention consists in a ruching for decoration, composed of sections connected together, each end to end to form a strip of indefinite length, each section being composed of a number of superposed sheets of tissue-paper cut partly across from one or both edges into narrow filaments, which form fringes, and are connected and held in place by the uncut portion of the paper, said filaments being opened out and caused to project in all directions, so as to cover the uncut portions of the paper, and give the ruching a fluffy appearance, like roped evergreen.

In the accompanying drawings, forming a part of this application, Figure 1 represents a side view of a single length of my improved ruching in an unfinished condition, showing the paper cut into filaments from both edges, leaving an uncut portion in the center. Fig. 2 represents an end view of the same. Fig. 3 represents a side view showing two sections or pieces of the cut paper to form the ruching, connected by a tape stitched to the uncut portions of both sections. Fig. 4 represents an end view of the form shown in Fig. 3. Fig. 5 also represents an end view of the form shown in Fig. 3, but with the filaments opened out to show the bushy circular contour of the ruching. Figs. 6 and 7 represent, respectively, side and end views of a modification. Fig. 8 represents an end view of the same with the filaments opened out; and Fig. 9 is a view of the ruche or article complete.

The same letters of reference refer to the same parts in all the figures.

In carrying out my invention I make a section of ruching, A, composed of several folds or strips of sheets of tissue-paper, the number of sheets being preferably about twelve, al-

though a greater or less number may be employed. I cut these strips transversely from one or both edges into narrow filaments, b, leaving an uncut portion, a, which connects all the filaments and keeps them in place. The sheets composing the section A may be secured together along the uncut portion by stitches c, as shown in Fig. 1, and the stitches may also serve to secure to the section A a tape, d, or strip of suitable flexible material, which serves to connect any desired number of sections A placed end to end, as shown in Fig. 3, the tape being stitched to all the strips to secure them together and strengthen the ruching or garland trimming. To complete the ruching, the filaments b are opened out or caused to stand out irregularly in various directions, as shown in Fig. 5, nearly or quite concealing the uncut portion of the paper at both sides, and giving the ruching a bushy or fluffy effect, somewhat resembling roped evergreen.

A modification is shown in Figs. 6, 7, and 8, in which the section A is centrally folded before being cut, the cutting being from one edge only of the manifold strip thus folded. This form may be considered as equivalent to one-half the form shown in Figs. 3, 4, and 5, and when it is used the sheets composing the section A are suitably secured together end to end to form suitable lengths of ruching, the connection having sufficient strength to enable the ruching to be looped or carried in loops or festoons from one point of support to another in decorating a room or building.

The sections are preferably secured together by the tape d, which is stitched to the sections, as above described, the tape being the best connecting medium that I am at present aware of. I do not limit myself, however, to the use of the tape, as the sections may be secured together by wire staples or fastenings, similar to those used in binding sheets of paper together in book-form, or by other suitable means.

This improved ruching gives a very rich and pleasing effect, and is admirably adapted for the decoration of walls, pillars, arches, &c. When made of green tissue-paper, its effect as an evergreen decoration is soft, pleasing, and aesthetic, and much superior to that of the natural roped evergreen above referred to;

and it possesses the additional advantage over the last-named decoration of being less expensive in most large cities at least, and much more durable, and in addition is lighter, 5 cleaner, and more readily handled, and will not crumble when removed.

It is well known that the natural evergreen soon withers and fades, and is so brittle that bits of it are constantly falling. These objections, it is obvious, are not met with in my improved ruching, and the latter may be kept indefinitely, and used on many different occasions.

I am aware that strips of paper have been 15 superposed and cut partly across into filaments and bound upon a stick or handle to form a duster or brush; but such strips have not been connected end to end to form a strip of indefinite length with the filaments opened 20 out to give the strip a massive, roped, evergreen-like effect.

I am also aware that apparel trimming has been made by superposing strips of ribbon or other textile fabric, and fraying the edges of the 25 strips to convert the ends of the warp threads into fringes resembling fur or down. Such trimming, however, is not adapted for use on a large scale for the decoration of rooms, because of its cost, and also of the fact that it 30 does not resemble roped evergreen, the filaments of its fringes being too fine—unlike my ruching, which has comparatively coarse filaments produced by cutting the tissue paper.

I am also aware that strips of paper have 35 been secured between two twisted wires to form a ruching for decorating purposes; but in this device the wires are liable to untwist and release the paper.

In view of the above I do not claim either 40 of the above-named inventions, my invention being superior to either as a ruching for decorating, not only in appearance, but in ease of manufacture and durability.

I claim—

45 1. The fringed ruching or garland trimming consisting of numerous strips or folds of

paper secured together by stitches and a strengthening strand or tape, and cut nearly across from their edges into filaments, forming fringe, which is raised, opened, and spread 50 into a light fluffy form, producing a full, bushy, and feathery effect, as described.

2. As a new article of manufacture, for decorative purposes, the ruching or garland trimming composed of manifold strips of paper 55 having their edges cut into filaments or fringe, the folds and different lengths thereof being united together into suitable lengths, and having the cut filaments opened and spread into a bushy or fluffy form to produce a garland, 60 as described.

3. The herein-described process of manufacturing the fringed ruching, or garland trimming, which consists in cutting manifold sheets of paper into strips of the desired width, 65 then cutting the folds into filaments, so as to leave a longitudinal uncut portion, securing the folds, and different lengths thereof together, then opening and spreading filaments of the fringed portion, whereby the ruching is given 70 a fluffy or feathery rounded appearance.

4. The method herein described of producing a ruching of paper, consisting of first cutting the required number of sheets of paper into numerous strips, then superposing a number of said strips, then cutting the combined strips into filaments to near their center, then uniting the sections formed by the strips by means of stitching them to flexible material, such as fabric, and then loosening them to 80 give the same a fluffy or feathery appearance until it approaches a circular form, as described.

In testimony whereof I have signed my name to this specification, in the presence of 85 two subscribing witnesses, this 18th day of February, A. D. 1881.

BENJAMIN NOYES.
